United States Patent Office

Des. 218,828
Patented Sept. 29, 1970

218,828

COMBINED TAPE RECORDER AND CARTRIDGE SELECTOR THEREFOR

Richard V. McCool, 9852 Fairfax Square,
Fairfax, Va. 22030

Filed Sept. 27, 1968, Ser. No. 13,741

Term of patent 14 years

Int. Cl. D14—01

U.S. Cl. D26—14

FIG. 1

FIG.2

FIG. 1 is a front perspective view of a combined tape recorder, and cartridge selector therefor, showing my new design;

FIG. 2 is a rear perspective thereof, and

FIG. 3 is a side elevation thereof.

The broken lines are shown for illustrative purposes only and form no part of the claim.

I claim:

The ornamental design for a combined tape recorder and cartridge selector therefor, substantially as shown and described.
